DISPLAY STAND FOR A TOY

Robert Roland Ruby, 8562 Harris Ave.,
Baltimore, Md. 21234

Filed Mar. 27, 1967, Ser. No. 6,390

Term of patent 7 years

(Cl. D80—9)

FIG. 1

The characteristic feature of my design resides in the circular base portion shown in the drawing.

I claim:

The ornamental design for a display stand for a toy, as shown and described.
